US00D495869S1

(12) **United States Design Patent** (10) Patent No.: **US D495,869 S**
Troitski et al. (45) Date of Patent: **** Sep. 14, 2004**

(54) **COMBINED KEY CHAIN WITH
TRANSPARENT PENDANT CONTAINING A
LASER-INDUCED PORTRAIT**

(75) Inventors: **Igor Troitski**, 853 Arrowhead Trail, Henderson, NV (US) 89015; **Karen Cashman**, Las Vegas, NV (US)

(73) Assignee: **Igor Troitski**, Henderson, NV (US)

(**) Term: **14 Years**

(21) Appl. No.: **29/169,737**

(22) Filed: **Oct. 28, 2002**

(51) LOC (7) Cl. **15-01**

(52) U.S. Cl. **D3/208**

(57) **CLAIM**

The ornamental design for a combined key chain with transparent pendant containing a laser-induced portrait, as shown.

DESCRIPTION

FIG. 1 is a front elevational view of a combined key chain with transparent pendant containing a laser-induced portrait showing my new design;

FIG. 2 is a left elevational view thereof; and,

FIG. 3 is a rear elevational view thereof.
